J. REISER

REED STRUCTURE

Filed March 3, 1927

WITNESS

W. Shell

INVENTOR,

John Reiser,

BY *John Edward*,
ATTORNEY

UNITED STATES PATENT OFFICE.

JOHN REISER, OF ROCHELLE PARK, NEW JERSEY.

REED STRUCTURE.

Application filed March 3, 1927. Serial No. 172,504.

This invention relates to warping machines and especially to the reeds used in such machines. In the ordinary so-called "cross-reed" for warping machines (the 5 reed used for forming the cross in the warp) the dents become worn or cut by the warp threads because the dents are all arranged in parallel planes whereas the threads of the warp, except those at the exact center, 10 all have some obliqueness, so that the threads contact therewith. Consequently the reed has frequently to be repaired or renewed; the reeds of this type are expensive not only on account of their length but 15 because their function in forming the cross in the warp requires the presence between certain of their dents of stops or blocks for contact by the threads. Of course the degree of convergence of the threads of the 20 warp varies in different warps. The object of this invention is to provide a structure for maintaining separated the advancing threads of a warp including, with a support, a unitary reed therein flexible to different degrees of curvature around an axis 25 parallel with one face of the reed and extending lengthwise of its dents. The invention also contemplates the provision in said structure of adjustable means to gage 30 the degree of curvature of the flexed reed. In the preferred form this gaging means is also means for effecting the actual flexing of the reed in situ. The reed, further, may well have some elasticity.

35 In the drawing,

Fig. 1 is a side elevation of a warping machine carriage embodying the invention;

Fig. 2 is a top plan view thereof, partly in section;

40 Fig. 3 is an elevation thereof as seen from a position looking toward the warping machine, certain parts being in section;

Fig. 4 is a section on line 4-4, Fig. 2; and

45 Fig. 5 is a vertical sectional view on a larger scale, illustrating a detail.

The warping machine carriage is indicated at 1 and at its outer end it may have some suitable means to support the structure 50 for maintaining separated the advancing threads of the warp (the converging margins of which are indicated at 2-2, in Fig. 2), such means in the present case being a rail 3 longitudinally grooved, as at 4, in its 55 top face, a pair of posts 5 upstanding from the rail and a removable top rail or cap 6,

grooved longitudinally in its under face and suitably apertured to receive and be fitted over the posts 5.

The hereinbefore mentioned support in the present case is a rectangular frame 7, which may be of any material, as wood. The reed is shown at 8. The construction of this reed is not material so long as it is flexible in the way hereinafter pointed out. 60 But in the present case it follows the usual form in that it comprises an elongated rectangular marginal portion 8^a and the dents 8^b with their thread-stops 8^c, said dents being arranged in parallel planes at right 65 angles to the long sides of the marginal portion 8^a. The entire reed may be composed of metal. The reed is flexible around an axis parallel with one face thereof and extending lengthwise of its dents or (the reed 70 being in operative position) around a vertical axis. In its broadest concept my invention is not concerned with whether or not the reed is elastic, as well as flexible, but in the preferred form it preferably is so. 75 The structure embodying the said support and reed includes adjustable means to flex the reed to a pre-determined curvature around said axis and, when the reed is elastic, to maintain it so flexed. This means is 80 as follows: On the top and also on the bottom bar of the rectangular marginal portion 8^a of the support 8 are arranged two spaced pairs of lugs 9 between which the reed-margin is adapted to be received and 85 thereupon held at its center. The reed may be engaged with these lugs by entering it endwise between them. On each end of the reed is a projecting tongue 10 and these are abutted by thumb screws 11 which are 90 screwed into the upright end- or side-bars of the support 7.

The structure comprising the reed and support, assembled as described, is adapted to be supported in the carriage by setting 100 the lower bar of the support 7 in the groove 4 of the rail 3 and then fitting the removable rail 6 over the posts and so that its groove receives the top bar of support 7.

105 It will be seen that the operator can adjust the reed in the support, to wit, by flexing it, to any necessary degree of curvature as viewed in plan so that the dents thereof shall be respectively in planes which are more or less parallel with the warp threads.

110 My invention is not limited to the adjustment of the reed being effected while it is

in the support 7, or to the reed being elastic. If the reed were merely flexible, the means 9—10 would at least serve for gaging the degree of curvature of the flexed reed.

5 The term "flex" as herein used connotes changing the curvature by constraint and is not restricted to bending to increase the curvature.

Having thus fully described my invention
10 what I claim and desire to secure by Letters Patent is:—

1. A structure to maintain separated the threads of a warp including a support and a unitary reed therein flexible to different degrees of curvature around an axis parallel with one face thereof and extending lengthwise of its dents, said structure having means, adjustable lengthwise of the warp, to gauge the degree of curvature of the
15 flexed reed.

2. A structure to maintain separated the threads of a warp including a support and a unitary reed therein flexible to different degrees of curvature around an axis parallel with one face thereof and extending
20

lengthwise of its dents, said structure having means, adjustable lengthwise of the warp, to flex the reed to a pre-determined degree of curvature.

3. A structure to maintain separated the threads of a warp including a support and an elastic unitary reed therein flexible to different degrees of curvature around an axis parallel with one face thereof and extending lengthwise of its dents, said structure having means, adjustable lengthwise of the warp, to flex the reed to a pre-determined degree of curvature.
30

4. In combination, a unitary flexible reed and a support therefor having three spaced bearing means against one of which the reed at its intermediate portion presses in one direction lengthwise of the warp and against the other two of which the reed at its respective ends presses in the relatively opposite direction, one of said means being adjustable lengthwise of the warp.
35

In testimony whereof I affix my signature.

JOHN REISER.
